UNITED STATES PATENT OFFICE.

FRANK SOUTHARD, OF SOUTHAMPTON, ENGLAND.

MODE OF MANUFACTURING PEDAL-CRANKS FOR VELOCIPEDES.

SPECIFICATION forming part of Letters Patent No. 445,303, dated January 27, 1891.

Application filed October 17, 1890. Serial No. 368,472. (No model.) Patented in England November 29, 1888, No. 17,408.

To all whom it may concern:

Be it known that I, FRANK SOUTHARD, residing at Southampton, England, have invented an Improved Method of Manufacturing Pedal-Cranks for Velocipedes, (which has been patented to me in Great Britain under No. 17,408, dated November 29, 1888,) of which the following is a specification.

My invention relates to the treatment of the metal and the formation of the pedal-cranks of velocipedes, and has for its object the production of a crank that shall be considerably lighter but as strong as those at present in use.

My improved cranks, as hereinafter fully described, are especially applicable to light velocipedes wherein the consequent diminished weight of the cranks will be found to be a further advantage, especially in the case of racing-machines.

My invention consists in twisting the cranks so as to form spiral convolutions.

I have found from my experiments that when a bar of metal is twisted as above described, and when sufficiently heated, it is capable of resisting torsional stress to a far greater extent than otherwise. It is well known that the ordinary cranks of velocipedes have to be made of a considerable section in order to resist the torsional stress produced by the pressure of the foot on the pedal.

In order that my invention may be the better understood, I now proceed to describe the same in relation to the drawings hereunto annexed, reference being had to the letters marked thereon.

Figure 1 shows a side view of an ordinary crank as at present in use. Fig. 2 is a view of a crank of reduced dimensions before twisting. Fig. 3 is a view of the crank in Fig. 2

twisted according to my invention. Fig. 4 is a cross-section through line A B in Fig. 3, showing the fluted contours of the convolutions. Figs. 5, 6, and 7 represent cranks having spiral convolutions of different pitches to suit various requirements. Figs. 8 and 9 illustrate my crank after the spiral ridges have been removed by turning or otherwise.

The twisting or spiraling may be imparted by means of any of the usual appliances, and preferably after the said cranks have been stamped out plain in the first instance of the reduced size, as shown in Fig. 2, and after having been sufficiently heated. The said cranks may be of any suitable shape in cross-section— such, for instance, as fluted, square, round, or other convenient form, as may be desired. They may be used just as left after the twisting operation, or may be machined to any shape, as desired.

My cranks, as above described, would be used in pairs—that is to say, the crank on the right-hand side of the machine would have right-hand spiral convolutions and that on the left side left-hand spiral convolutions.

What I claim, and desire to secure by Letters Patent of the United States, is—

The method of manufacturing pedal-cranks for velocipedes by twisting them in their length to increase their strength, substantially as described.

In testimony whereof I have signed my name to this specification in the presence of two subscribing witnesses.

FRANK SOUTHARD.
